(57) **CLAIM**

I claim the ornamental design for a workstation assembly, as shown and described.

DESCRIPTION

FIG. 1 is a rear perspective view of a workstation assembly, in use with its intended environment shown in broken lines; FIG. 2 is a front perspective view thereof; FIG. 3 is a front elevation view thereof; FIG. 4 is a rear elevation view thereof; FIG. 5 is a left side elevation view thereof; FIG. 6 is a top plan view thereof; and, FIG. 7 is a bottom plan view thereof.

The broken lines in FIGS. 1-7 are illustrative of an environmental structure only and form no part of the claimed design. The right side elevation view of the workstation assembly is a mirror image of the left side elevation view. Only the left side elevation view is illustrated.
